ELECTRICAL SYSTEM WITH OUTPUT SIGNAL VARYING LOGARITHMICALLY WITH RESPECT TO THE INPUT SIGNAL

Alfred Wilson Nolle, San Marcos, Tex., assignor to The Electrodyne Company, Boston, Mass., a corporation of Massachusetts

Application April 30, 1948, Serial No. 24,263

24 Claims. (Cl. 171—95)

1

Various methods and devices have heretofore been proposed for delivering an output current or voltage which is proportional to the logarithmic amplitude of an input voltage or current derived from some physical phenomenon to be evaluated or measured. Some of these systems utilize instruments in which logarithmic deflection of a pointer is obtained through the use of a nonlinear electromechanical device, or of arrangements which derive a logarithmic characteristic from special properties of circuit elements such as vacuum tubes or materials with selected conductivity characteristics.

It is one of the main objects of the present invention to provide a system of that type, which responds logarithmically to an input signal, merely through proper use of linear passive circuit elements without employing any peculiar operation characteristics of vacuum tubes or other circuit elements and which is, therefore, independent of such characteristics which are often uncontrollably variable, the system response being due only to the use of standard elements with regard to their most favorable unchanging and stable operation characteristics and is, therefore, reliable, exact, easy to maintain in proper operating condition and comparatively inexpensive.

In a broad aspect the invention contemplates an electrical system with an output signal varying logarithmically with respect to an input signal comprising an attenuation network having a logarithmic voltage-time characteristic, a source of potential proportional to the magnitude of the input signal, and a source of constant peak potential which, in different aspects of the invention, may be either a constant magnitude direct potential or an alternating potential having a wave shape with a constant peak amplitude. Connections are provided to energize the network from one of these sources and for applying the other source to the network as a comparative attenuation standard.

In other aspects the attenuation network is energized by either the potential proportional to the magnitude of the input signal source or by the source of constant peak potential as defined above, the other source being used as a comparative attenuation standard. In all aspects the network operates a timing device during the time interval required for attenuation between the limits of a potential equal in magnitude and opposite in polarity to the potential of the comparative standard and a potential with a magnitude determined by the magnitude of the energizing source thereby to obtain a function ex-

2

pressing in terms of time a logarithmic correlation of the amplitudes of the input and output signals.

In other aspects the attenuation network includes a reactive impedance and a series connected resistor with the energizing potential being supplied by a square wave generator, and the timing device including a vacuum tube amplifier. The tube has a grid and cathode connected to the output terminals of the attenuation network. The tube anode is connected in series with a unidirectional current limiter and a meter. The grid bias of the tube is such that current flows through the anode circuit and thus through the meter only during the time intervals required for attenuation between the limits of a potential equal in magnitude and opposite in polarity to the potential used as a comparative standard, and a potential with a magnitude determined by the magnitude of the potential of the energizing source and the attenuation rate of the network.

The latter, limiting potential is the potential of the network output terminals at the beginning of each succeeding cycle when a square wave potential having an amplitude proportional to the input signal is applied to the network as the energizing potential. When the network is energized by a square wave with a constant peak amplitude, the latter limiting potential is that potential across the network output terminals of which attenuation has taken place by the end of a half wave cycle.

In one specific aspect a capacitor and a resistor of an attenuation network are connected in series with a square wave generator. The anode of a rectifying diode for the positive portion of the input signal is linked with the input signal source, the associated cathode being coupled by a ripple filter with the cathode of a limited diode whose anode connects with the output terminal of the square wave generator. The cathode of a second rectifying diode for the negative portion of the input signal is likewise linked with the input signal source. A second ripple filter couples the anode of the second rectifying diode with the anode of a second limiter diode whose cathode connects with the generator output terminal.

To increase the sensitivity and linearity of the above diodes at low signal levels a connection is provided to a direct power source so that a small current continuously circulates therethrough whereby the amplitude of the square wave impressed upon the network is always proportional to the input signal. The direct power

source is also connected to the attenuation network through a resistor to impress a comparative attenuation standard potential thereupon.

The timing device includes two interconnected vacuum tubes each having a cathode, a grid and an anode. The first stage grid and cathode are connected to the output terminals of the attenuation network. The anode is coupled directly to the second stage grid and is also connected to the direct power source by means of a series resistor.

A second resistor links the second stage anode with the power source. A series connected meter and unidirectional current limiter provide a parallel path between the second stage anode and the power supply whereby during the time interval from the energization of the network by a negative wave from the square wave generator until the attenuation reaches a potential equal in magnitude and opposite in polarity to the comparative standard potential, the resultant negative potential on the grid prevents the first stage tube from conducting so that the positive potential on the second stage grid causes a current to flow through the meter whereby its indication is proportional to the duration of the current pulses applied thereto, thereby to express a logarithmic correlation of the amplitudes of the input and output signals.

Connections are also made between the direct power source and the meter to direct a reverse current therethrough thus preventing ambiguous indications when no current flows in the circuit of the second stage anode during intervals when the first stage grid is at a positive potential.

In another specific aspect the series connected capacitor and resistor of the attenuation network are coupled to the input signal source by means of a full wave rectifier and a ripple filter so that a negative potential proportional to the amplitude of the input signal is impressed upon the network as a comparative attenuation standard. The network is energized by a square wave generator with an output terminal connected to the input terminal of the network.

To maintain the amplitude of the square wave from the generator constant, the anode of a diode is connected to the generator output terminal. The diode-cathode is coupled to the more positive terminal of a bleeder resistor connected to the direct power source thereby to limit the positive peak amplitude of the generator output. The negative peak amplitude is limited by a second diode having an anode and cathode linked to the more negative terminal of the bleeder resistor and the generator output terminal respectively.

The output terminals of the network are connected with a timing device including two vacuum tubes interconnected as a two-stage amplifier with the first-stage grid and cathode coupled to the output terminals of the attenuation network. The first-stage anode is connected to the square wave generator by a series resistor and is also linked directly to the second-stage grid. The second-stage anode is connected to the direct power source by both a resistor and a parallel path including a unidirectional current limiter and a meter connected in series therewith whereby during the interval beginning at the time the potential of the attenuation network is equal in magnitude and opposite in polarity to the potential of the comparative standard and terminating at the start of the next half cycle by the reversal of polarity of the potential upon the

first stage anode, the meter indication is proportional to the duration of the current pulses applied thereto, thereby to express a logarithmic correlation of the amplitude of the input and output signals.

5 A feature of the invention is an electrical circuit for supplying a square wave with an amplitude proportional to an input signal. This circuit comprises two rectifying elements connected to the input signal source, one of these elements rectifying the positive portion of the signal, the other element rectifying the negative signal portion. A unidirectional element connects the respective rectifying elements in the opposite sense with the output terminal of a square wave generator whereby the amplitude of the square wave is limited to the magnitude of the positive and negative potentials impressed on the unidirectional elements by the respective rectifiers upon 10 the conduction of one of the unidirectional elements whenever the potential correlated therewith is exceeded.

15 Another feature is an electrical network for completely cutting off the flow of current in the output circuit thereof in response to a predetermined change in the potential of an input signal. This network comprises a two-stage amplifier including two interconnected vacuum tubes with the first-stage grid and cathode connected 20 to the output terminals of an input signal source. The first stage anode is connected to a direct power supply by a series resistor and is also linked directly to the second stage grid. The second stage anode is connected to the power supply by 25 both a resistor and a parallel path including a unidirectional element, a meter and the network output terminals connected in series between the anode and power supply whereby the application to the first stage grid of a signal having a potential characteristic to cause a current flow through 30 the resistor in series with the first stage anode results in a voltage drop which impresses upon the second stage grid negative potential sufficient to cut off the second stage tube so that a positive potential is impressed upon the unidirectional 35 element in the sense to prevent the element from conducting.

40 These and other objects, aspects and features of the invention will be apparent from the several 45 specific embodiments thereof illustrated in the accompanying drawings in which:

50 Fig. 1 is a block diagram of a simple embodiment of the invention whereby the output signal is logarithmically correlated to a constant input signal;

55 Fig. 2 is a graphical representation of the output potential of the attenuation network in Fig. 1 as a function of time;

60 Fig. 3 is a block diagram of a second embodiment of the invention whereby the output signal is logarithmically correlated to a varying input signal;

65 Fig. 4 is a detailed wiring diagram of the embodiment shown in Fig. 3;

70 Fig. 5 is a graphical representation of the input and output voltages of the attenuation network and the current through the meter M of Fig. 4 as a function of time;

75 Fig. 6 is a block diagram of a third embodiment of the invention showing another means whereby the output signal is logarithmically correlated to a varying input signal;

Fig. 7 is a wiring diagram of the embodiment shown in Fig. 6; and

Fig. 8 is a graphical representation of the input

and output voltages and the current through the meter M of Fig. 7 as a function of time.

In Fig. 1 is shown an embodiment of the invention whereby an elapsed interval of time as measured by an electrical timer T_r is proportional to the logarithmic amplitude of a voltage pulse applied across the terminals t_1 and t_2 of an input signal source. Terminals t_1 and t_2 are connected in series with a capacitor C and a resistor R of an attenuation network by one position (as shown) of a single pole double throw switch S1. When in the opposite position, the switch S1 provides a short circuiting connection to discharge the capacitor C.

One terminal of the resistor R is joined to the grid g of a vacuum tube V, the other resistor terminal being linked with the negative pole of an attenuation standard such as the battery B supplying a constant magnitude direct potential. The tube anode p is joined with the terminal of a "B+" power supply (not shown) through the solenoid of a relay S2. The normally opened contacts of the relay S2 are connected in series with a timing device such as the electrically driven timer T_r and the terminals a and c of a conventional power supply (not shown).

Operation of the above circuit can best be understood by referring to the diagram in Fig. 2 wherein the line E_r graphically represents the exponential relationship of the voltage drop across the resistor R as a function of time after a direct voltage of the magnitude E_p has been applied to the terminals t_1 and t_2 (Fig. 1). This relationship is also expressed mathematically as $E = E_p \exp(-t/RC)$, the well known expression for the charge or discharge of a capacitor through a series resistor, where R and C are the ohmic impedance of the resistor R and the capacitance of the capacitor C respectively and E is the voltage across the resistor after the elapse of a time t . Expressed in another manner

$$t = RC(\ln E_p - \ln E)$$

From the above it is evident that the time t_q for attenuation of the voltage across the resistor R to the constant potential E_q of the attenuation standard is, therefore, expressed as $t_q = RC(\ln E_p - \ln E_q)$.

As the magnitude of the impedance characteristics of the capacitor C, the resistor R and the attenuation standard potential E_q supplied by the battery B remain constant, it can be readily seen that the time t_q is a function of the natural logarithm of the signal input voltage E_p .

When a direct voltage is applied across the terminals t_1 and t_2 by the closing of the switch S1 to the position shown, the capacitor C begins to charge through the resistor R. The flow of current through the resistor R results in a voltage drop E_r initially sufficient in magnitude and of such polarity as to oppose the voltage of the battery B so that the grid g of the tube V becomes positive with respect to the cathode k . As long as the grid g is relatively positive, current flows in the anode circuit to energize the coil of the relay S2 and thereby to close its contacts. The closing of these contacts energizes the timing device T_r from the terminals a and c of a power supply (not shown) so that the measurement of a time period is started.

As shown by the diagram in Fig. 2, the voltage drop E_r across the resistor R attenuates until it reaches a point q where it is equal in magni-

tude and opposite in polarity to the voltage E_q of the battery B. As the grid g becomes negative the tube V no longer conducts and the circuit of the timer T_r is open. From the above it can be seen that the length of this elapsed time is a function of the input signal voltage and as measured by the timer T_r provides a logarithmic measure of the magnitude thereof.

In Fig. 3 is shown another embodiment with a more elaborate circuit whereby it is possible to obtain a continuous logarithmic indication of the magnitude of a varying input signal, for example, such as a signal from a microphone located in an acoustical test chamber.

The detailed wiring connections of this embodiment are shown in the diagram in Fig. 4. The terminals t_1 and t_2 of the microphone or other input signal source are connected by means of a coupling capacitor c_1 across a potentiometer r_1 the adjustable tap of which is joined to the control grid g_{11} of an amplifier such as the pentode vacuum tube V1.

The tube suppressor grid g_{13} and the cathode k_1 are linked together and grounded through the grid biasing resistor r_2 . The screen grid g_{12} is connected to a grounded bypass capacitor c_2 and to a direct power supply (described hereinafter) by means of a series resistor r_3 and the leads m and n . The power supply is similarly connected by the leads m and n to the anode p_1 through a series resistor r_4 . The anode p_1 is also connected by a coupling capacitor c_3 with the anode p_{21} and the cathode k_{22} of a double diode vacuum tube V2, which provides rectification of the negative and positive portions of the amplified input signal. The remaining anode p_{22} and cathode k_{21} are linked with the anode p_{31} and the cathode k_{32} of a second double diode vacuum tube V3 by the resistors r_6 and r_7 respectively. The bypass filter capacitors c_4 and c_7 are connected between the respective ends of the resistor r_6 and ground. Each end of the resistor r_7 is grounded analogously by the capacitors c_5 and c_6 respectively. The commonly connected cathode k_{22} and the anode p_{21} of the tube V2 are linked to a point x by means of a resistor r_8 . The cathode k_{21} also connects with the point x through two series resistors r_9 and r_{11} . Resistors r_{12} and r_{13} connect the anode p_{22} to the point x in similar manner. By choosing the resistors r_{12} and r_{13} so that they have the same ohmage as the resistors r_9 and r_{11} respectively, the point x is maintained at an average potential midway between the positive and negative potentials appearing at the input terminals of the resistors r_7 and r_6 respectively whenever an amplified input signal is rectified by the diodes in tube V2. The mid-potential point x is connected to ground by a capacitor c_8 .

The connecting of the large capacitor c_5 in parallel with the load resistor r_9 of the positive diode rectifier of the tube V2 increases the direct voltage output of the rectifier and reduces the ripple component in the rectifier output as the capacitor charges nearly to the peak voltage of the rectifier output. The capacitor c_5 also makes the rectifier direct current output proportional to the peak rather than the average value of the A.-C. input signals. Further filtering action is provided by the resistor r_7 and the capacitor c_6 so that a relatively constant direct potential is impressed on the cathode k_{32} . The

negative potential developed across the load resistor r_{12} is increased and filtered in analogous manner by the capacitors c_4 and c_7 and the resistor r_6 before it is impressed on the anode p_{31} .

To improve the rectifying and limiting performance at low signal levels of the double diode vacuum tubes V_2 and V_3 respectively, a small direct current is passed through these tubes in the absence of an input signal. This direct current is obtained from an adjustable tap t_3 of a bleeder resistor br_5 which is one of a plurality of such resistors including br_1 , br_2 , br_3 , br_4 and br_8 series-connected between a positive terminal y of the direct power supply and ground. The common junctions between resistors br_2 and br_3 and between resistors br_4 and br_5 are also connected to ground through the resistors br_6 and br_7 respectively.

As stated above r_9 and r_{12} are the load resistors for the double diode V_2 across which are developed the positive and negative potentials respectively resulting from an input signal from the amplifier V_1 . The resistors r_{11} and r_{13} are of much smaller ohmage than the resistors r_9 and r_{12} and comprise the combination across which the potential difference between the tap t_3 and ground appears so that a small adjustable direct current flows through all the diode elements continuously in two parallel paths regardless of whether or not an input signal is present. The first path includes r_{12} — p_{22} — k_{22} — p_{21} — k_{21} — r_9 to ground. The second parallel path includes r_{12} — r_6 — p_{31} — k_{31} — p_{32} — k_{32} — r_7 , r_9 to ground.

The flow of this small direct current insures that at low input signal levels, the diodes are passing sufficient current so that their respective plate resistances do not reach the high values found in the very low current regions. A second advantage of avoiding the low current regions is the tendency under such operating conditions of a diode to act as a battery producing a direct output voltage in the absence of an alternating input voltage as a result of the finite emission velocity of the electrons and of contact different of potential between the respective plates and cathodes.

The anode p_{32} and the cathode k_{31} of the tube V_3 are linked with the control grid g_{41} of an amplifier tube V_4 . These electrodes are also interconnected with point x through the resistors r_{14} and r_{16} . The cathode k_4 is grounded through a grid biasing resistor r_{17} . The anode p_4 and the screen grid g_{42} are connected to the lead m from the direct power supply by means of the series resistors r_{18} and r_{19} respectively. The screen grid g_{42} is also connected to ground through a conventional bypass capacitor c_9 .

It will be noted that the cathode resistor r_{17} is not bypassed by a capacitor so that the alternating component of the anode current flows through the resistor r_{17} as well as the impedance of the anode circuit. This current produces a voltage drop across the resistor r_{17} which is impressed upon the cathode k_4 but not upon the grid g_{41} and is, therefore, a part of the effective signal impressed between the grid g_{41} and the cathode k_4 . Such a signal is of the same frequency but opposite in phase to the square wave on the grid g_{41} so that it constitutes a current type of feedback which has two results. First, the gain of the V_4 amplifier stage is relatively independent of individual tube characteristics or variations in power supply voltage; and second, the output impedance of the tube V_4 (the

effective anode resistance) is large as compared with the impedance of load resistor r_{18} so that the following RC circuit [described in detail below] is driven effectively by a generator with an impedance approximately equal to the resistor r_{18} and which is not critically dependent upon the anode resistance of the tube V_4 .

An energizing potential with a square wave shape obtained by clipper action from one of the anodes p_{61} of a double triode vacuum tube V_6 is also impressed upon the grid g_{41} of the tube V_4 by coupling the anode p_{61} to the common junction of the resistors r_{14} and r_{16} respectively by means of a capacitor c_{10} . The frequency of the wave is determined by a large sinusoidal voltage from one of the secondary windings T_1 's of a power supply transformer T_1 which is applied between the grid g_{61} and the grounded cathode k_{61} by a limiting resistor r_{10} . The direct current for the anode p_{61} is supplied from the direct power supply through a series resistor r_{15} and the lead n .

As described, heretofore, the grid g_{41} is connected to the cathode r_{31} and the anode p_{32} of the double diode V_3 . These connections prevent the grid g_{41} from becoming more positive than the cathode k_{32} or more negative than the anode p_{31} because if either potential is exceeded the corresponding diode conducts which is the equivalent of connecting the grid g_{41} to either k_{32} or p_{31} (as the case may be) by means of a small resistor (the internal resistance of the respective diode). The potentials on the cathode k_{32} and the anode p_{31} , respectively, with reference to the point x which is connected to g_{41} by the resistors r_{14} and r_{16} are determined by the magnitude of the rectified signals.

As can be readily seen, the signal on the grid g_{41} consists of a square wave with a peak to peak amplitude proportional to the input signal amplitude and with a frequency of the potential at the terminals a and c of the alternating power source.

Transformer T_1 also is used in the conventional manner as the voltage step-up device of the direct current power supply to which reference has been made heretofore. The primary winding T_1 'p is connected to the terminals a and c of a single phase alternating power supply of the usual type (not shown). The center tap of the secondary winding T_1 's is grounded and the end terminals are joined with the anodes a_{71} and a_{72} respectively of a full wave rectifier tube V_7 . The lead from the cathode k_7 branches to connect with both the grounded filter capacitor c_{71} and a tap on the winding of the hum-bucking filter choke L . The end terminals of the choke winding are grounded through the filter capacitors c_{72} and c_{73} respectively. The lead n supplying power to the respective tube anodes and the first bleeder resistor br_1 are connected to the common junction y of the winding of the choke L and the filter capacitor c_{73} .

The anode circuit of the tube V_4 connects with one plate of a capacitor C of an attenuation network which also includes the series connected resistors R_1 and R_2 . Resistor R_2 is made adjustable to obtain a means of calibrating the scale factor of an output meter M . The connection between one end of the resistor R_1 and the capacitor C is completed when a switch S_3 is thrown to the position shown. The lower terminal of the resistor R_2 is connected to ground through a capacitor c_{11} and to the common junc-

tion of the bleeder resistors br_4 , br_5 and br_7 to provide a positive reference voltage of constant magnitude as a comparative attenuation standard.

The capacitor c_{11} provides a low impedance path to ground for alternating currents in the attenuation network so that surges in the bleeder circuit resulting from the passage of pulses of direct current through the meter M (as will be described in detail hereinafter) do not produce appreciable voltage changes in the attenuation network. Conversely, voltage changes in the attenuation network do not produce appreciable alternating voltages in the bleeder circuit so that neither the meter circuit nor the rectifier circuits which are connected through the tap t_3 are affected.

The resistors R_{11} and R_{12} and the capacitor c_{12} are also connected in series between the switch S_3 and ground so that the throwing of the switch changes the scale factor of the instrument. A reference voltage is obtained in an analogous manner by joining the common terminal of the resistor R_{12} and the capacitor c_{12} to the common terminal of the bleeder resistors br_3 and br_4 . It will be noted that with the switch S_3 in either position the effective resistance of the attenuation network in series with the capacitor C also includes the generator impedance of the vacuum tube V4.

The capacitor C is also coupled by a resistor r_{30} with one grid g_{51} of a double triode V5. The corresponding cathode k_{51} is grounded, bias for the grid g_{51} being supplied from the bleeder circuit through resistors R_1 and R_2 (or R_{11} and R_{12} as described heretofore). The anode p_{51} is coupled directly to the second grid g_{52} so that the double triode acts as a two stage amplifier. The cathode k_{52} is joined directly to the common junction of the bleeder resistors br_2 and br_3 . The anode p_{52} is connected to the cathode k_{62} of the second double triode in the vacuum tube V6. The direct power supply is connected to both anodes p_{51} and p_{52} of the tube V5 by the lead n and the series resistors r_{21} and r_{22} respectively.

The grid g_{62} and the anode p_{62} are linked so that the second triode enclosed in the envelope of tube V6 acts as a diode. These electrodes are also connected to the negative terminal of the milliammeter M by means of the series resistors r_{23} , r_{24} and r_{26} . The positive meter terminal is connected to the common junction of the bleeder resistors br_1 and br_2 . A capacitor c_{13} connected between the positive meter terminal and the junction of the resistors r_{24} and r_{26} shunts the alternating current components around the meter M and also prevents rapid changes of meter indication. A glow tube N is connected between the positive meter terminal and the anode p_{62} to maintain a constant voltage across the meter M and the series resistors r_{23} , r_{24} and r_{26} . Resistor r_{23} is made adjustable and determines the current sensitivity of the meter circuit.

Whenever a signal impressed across the terminals t_1 and t_2 results in a potential upon the grid g_{51} which is negative with respect to the ground potential and greater in magnitude than the positive voltage $+E_q$ (equal to the voltage drop in the bleeder resistor br_7) biasing the grid g_{51} , thereby making the grid relatively more negative, the current flowing through the anode circuit of the first triode of tube V5 and hence

through the resistor r_{21} is reduced. The reduction in the voltage drop across the resistor r_{21} causes the directly coupled grid g_{52} of the second V5 triode to become relatively more positive with respect to the cathode k_{52} , which is at the positive potential above ground equal to the voltage drop in the bleeder resistor br_6 , whereupon the accompanying increase in current flow in the anode circuit of the second triode results in an increase in the voltage drop in the resistor r_{22} . The cathode k_{62} in tube V6 being connected to the resistor r_{22} becomes negative with respect to the anode p_{62} so that diode-connected triode in tube V6 conducts and a current flows (in the conventional sense) from the point y of the power supply through the bleeder resistor br_1 , the meter M, the series resistors r_{26} , r_{24} and r_{23} , the anode p_{62} , the cathode k_{62} , the anode p_{52} , the cathode k_{52} and the resistor br_6 to ground.

With no input signal at the terminals t_1 and t_2 , the positive potential $+E_q$ is impressed between the grid g_{51} and the cathode k_{51} of the tube V5. The voltage drop in the resistor r_{21} resulting from current flow through the first triode impresses a potential on the grid g_{52} sufficiently negative with respect to the cathode k_{52} (which is at the positive potential of the bleeder resistor br_6) to prevent the second triode from conducting. When the second triode is not conducting its anode p_{52} and the cathode k_{62} of the second triode in the tube V6 are at the positive potential of the power supply terminal y and hence at a greater potential by the amount of voltage drop in resistor br_1 than the anode p_{62} so that no current flows through the second triode of the tube V6 and the meter M.

The negative terminal of the meter M is also connected to the movable contact of a single pole double throw switch S_4 through a resistor r_{27} . Each of the two stationary contacts of the switch S_4 is joined to the adjustable taps of the respective potentiometers r_{28} and r_{29} , the windings of which are connected in parallel with the bleeder resistor br_1 . The switch S_4 is mechanically linked with the switch S_3 so that both switches are operated conjointly when a change of scale factor is required.

With the switch S_4 in the position shown current from the power supply point y flowing through the potentiometer r_{28} establishes a potential difference across the meter M and its series resistor r_{27} . When in the absence of an input signal (as described above) no current is directed through the meter M by the tube V6, the voltage drop in the potentiometer r_{28} circulates a reverse direct current through the meter M and the series resistor r_{27} . When the switch S_4 is thrown in the opposite position to that shown, the potentiometer r_{29} circulates a reverse current through the meter circuit in an analogous manner. In either case the current is in such a direction as to move the meter indicator off scale whereby in the absence of an input signal the response of the instrument is unambiguous. The amount of reverse meter current is controlled by the adjustable taps of the potentiometers r_{28} and r_{29} .

The following table lists the characteristics of the circuit elements of an instrument which has a response of 20 decibels with the resistors R_1 and R_2 in series with the capacitor C of the attenuation circuit. This instrument has a 30 decibel response with the resistors R_{11} and R_{12} connected in series with capacitor C.

Operation of the embodiment in Fig. 4

Operation of the above embodiment of the invention can best be understood by referring to the block diagram (Fig. 3) and the voltage time curves of the input and output of the attenuation network shown in Fig. 5. As described in detail heretofore, the input signal applied between the terminals *t₁* and *t₂* by a microphone or other input signal source is amplified and rectified by the tubes *V₁* and *V₂* respectively whereupon it appears as positive and negative potentials balance with respect to the point *x* (Fig. 4) on the cathode *k₃₂* and the anode *p₃₁* respectively of the tube *V₃*.

The voltage *E_p* (top curve Fig. 5) impressed upon the attenuation network is obtained from the square wave output voltage from the generator tube *V₆*, the amplitude of which is proportional to the magnitude of the input signal source because of the limiting action of the tube *V₃*, as described heretofore. The output voltage of the attenuation network, as impressed upon the grid *g₅₁*, is shown in the center curve of Fig. 5 as *E_r*. The peak of this voltage is $E_p(1+\delta)$ where $\delta=\tanh(T/4RC)$, *T* being the period of the square wave and *R* and *C* the total ohmic resistive impedance and the capacitance of the attenuation network. The increment δE_p is added to the input voltage *E_p* because the capacitor *C* charges almost completely during each half cycle of the square wave. During the negative portion of the cycle when *E_r* is greater in magnitude than *E_q* (the positive voltage bias sup-

plied by the bleeder resistor *br₁*), a negative potential is impressed upon the grid *g₅₁* of the tube *V₅* thereby resulting in a current flow through the meter *M*. After the output voltage *E_r* has 5 attenuated beyond the point *q*, *E_r* is lesser in magnitude than *E_q* so that the grid *g₅₁* becomes positive, thereby blocking the second triode in the tube *V₅* and the current flow through the meter *M* in the manner described in detail heretofore.

10 The above action is clearly shown in Fig. 5. As each successive negative voltage square wave peak is applied to the attenuation network, its amplitude is attenuated according to the expression:

$$E=(1+\delta) E_p \exp(-t/RC)$$

During the portion of the attenuation when the grid *g₅₁* is negative, a pulse of current flows through the second triode of tube *V₅* and through 20 the meter *M*. After the negative voltage has attenuated to the point *q* where it is equal in magnitude to the positive bias voltage *E_q*, further attenuation causes the grid *g₅₁* to come under 25 the influence of the dominating positive voltage *E_q*, thereby stopping the current flow through the meter *M*. The elapsed time *t_q* for the attenuation is expressed:

$$tq=RC[1nE_p(1+\delta)-1nE_q]$$

30 *R*, *C* and *E_q* are constants and δ is constant for any given frequency so that:

$$tq=\text{constant} \times 1nE_p$$

35 i. e., the elapsed time is proportional to the natural logarithm of amplitude of the input signal. This relationship holds as long as the amplitude of *E_p* is small enough so that *t_q* is less than one-half of the period *T* of the square wave.

40 The meter *M* acts as a timing device measuring the average energy level in the successive current pulses. As the voltage is maintained constant by the glow tube *N*, only a measurement of current is necessary to obtain an energy indication so that a millimeter can be used. The 45 voltage limiting action of the glow tube *N* maintains a constant current flow during each pulse so that the indication of the meter is proportional to the time duration of the pulses and is, therefore, proportional to the natural logarithm 50 of amplitude of the input signal. The movement of the meter pointer during the intervals between pulses is eliminated by the electrical damping provided by the capacitor *c₁₃*. It will of course be understood that other integrating electrical 55 instruments, for example a watt hour meter, a volt-meter measuring the voltage across a capacitor charged by the pulses, or a cathode-ray oscillograph, may be used to replace the meter *M* as a timing device.

60 In Figs. 6 and 7 is shown a third embodiment of the invention whereby a continuous varying input signal is employed to produce a varying direct voltage which serves as a standard of attenuation. A square wave having fixed frequency and amplitude is then attenuated by a network having a logarithmic voltage-time characteristic to obtain a logarithmic response.

65 The input signal is impressed upon the terminals *t₁* and *t₂* (Figs. 6 and 7) which are coupled to the respective ends of a potentiometer *r₁* by means of a coupling capacitor *c₁*. The adjustable tap of the potentiometer *r₁* is linked with the grid *g₁* of an amplifying vacuum tube *V₁*. The grid bias is supplied by connecting the tube 70 cathode *k₁* to ground through a biasing resistor

2. A coupling capacitor c_2 links the circuit of the tube anode p_1 with the anode p_{21} and the cathode k_{22} of the double diode rectifier vacuum tube V_2 . The anode p_{22} and the cathode k_{21} of tube V_5 are joined to the ungrounded and grounded input terminals, respectively, of a load resistor r_{12} . The direct potential developed across the resistor r_{12} is applied to a ripple filter comprising a resistor r_6 connected in series between the anode p_{22} and the input terminal of a resistor R of an attenuation network. The filter capacitors c_4 and c_7 are connected between the terminals of the resistor r_6 and ground in parallel with the load resistor r_{12} .

The lead from the other terminal of the resistor R branches to connect with the grid g_{51} of a double triode tube V_5 through a resistor r_{30} and with the capacitor C which is the other element of the attenuation network. The capacitor C is also connected with the anode p_{51} of a double triode tube V_6 so that a square wave is impressed upon the attenuation network when the grid g_{51} is excited by the sine wave from the transformer secondary T_1 s.

The amplitude of the square wave is maintained constant by the limiting action of the double diode tube V_3 , the anode p_{31} and cathode k_{32} of which are joined with the anode p_{51} of the square wave generator tube V_6 . The anode p_{32} and the cathode k_{31} are connected to the respective terminals of a bleeder resistor r_{71} which is connected in series with the bleeder resistors r_{72} and r_{73} between the B_+ terminal of the direct power supply and ground. It can be seen that the positive and negative peaks of the square wave are limited to the level of the potentials maintained at the cathode k_{31} and the anode p_{32} by the voltage drop in the bleeder resistors r_{71} and r_{72} , as whenever either the positive or negative potential level is exceeded the corresponding diode conducts to complete a relatively low resistance path to ground.

With the exception that the anode p_{51} of the tube V_5 is connected to the anode p_{61} rather than directly to the direct power supply by means of the resistor 21 , the tubes V_5 and V_6 , the meter M and the associated circuits are connected and operate in analogous manner to the corresponding elements of the preceding embodiment which have been described in detail heretofore. By the above-mentioned change in anode power supply, during the negative half of each square wave on the grid g_{51} , the tube V_5 is prevented from energizing the meter M in the manner described heretofore because such negative potential is also impressed upon the anode p_{51} and the second grid g_{52} . With a negative potential on the grid g_{52} , the second triode in tube V does not conduct and no current flows through the meter M to give a false indication.

Operation of the embodiment in Fig. 7

Operation of the above-described circuits can best be understood by reference to the block diagram (Fig. 6). A square wave potential from the square wave generator tube V_6 and maintained at constant amplitude by the limiter tube V_3 , is impressed continuously upon the capacitor C of the attenuation network. The signal from the input signal source is impressed upon the grid g_1 of the amplifying tube V_1 of the terminals t_1 and t_2 . The output of tube V_1 is rectified by the double diodes in the tube V_2 , passes through the ripple filter, and is thereupon impressed in the grid g_{51} .

As described in connection with the operation of the embodiment shown in Fig. 4, the capacitor C of the attenuation network does not discharge completely during the period T' (Fig. 8) between successive waves so that the voltage impressed upon the network by each successive cycle is $E'p(1+\delta)$. As discussed in detail heretofore, the attenuation time may be expressed $tq=RC[1nE'p(1+\delta)-1nE'q]$, wherein the term $1nE'q$ has a negative algebraic sign. By measuring the time interval $t'q$ (Fig. 8), this negative quantity is eliminated as:

$$t'q=T/2-RC[1nE'p(1+\delta)-1nE'q]$$

15 where T is the period of the square wave, and R and C are the values of the effective resistance and capacitance, respectively, of the attenuation network which are constant so that:

$$t'q=\text{constant}+RC1nE'q$$

i. e., $t'q$ is proportional to the natural logarithm of the input signal amplitude.

As is clearly indicated in Fig. 8, at the start of each positive cycle of the square wave, a positive potential $E'p(1+\delta)$ is impressed upon the grid g_{51} so that no current flows through the meter M , because of the blocking action of the tube V_5 , as was described in detail with respect to the first embodiment. As the capacitor C charges the current flowing in the attenuation network, and, therefore, the voltage drop across the resistor R decreases until it is equal in magnitude and opposite in polarity to the rectified signal $-Eq$ as at points q' , q'' , and q''' . The grid then becomes negative thereby causing the second triode in the tube V_6 to conduct. This conduction takes place for a time $t'q$, i. e., until the beginning of the next negative cycle of the square wave impresses a negative potential upon the anode p_{62} as described above.

The successive surges of current through the meter M are integrated and averaged thereby, in the same manner as described in detail heretofore, so that the resulting meter indication is a logarithmic measure of the magnitude of the input signal.

I claim:

1. An electrical system with an output signal varying logarithmically with respect to an input signal comprising an attenuation network having a logarithmic voltage time characteristic, a source of potential with a magnitude proportional to said input signal, a source of constant peak potential, connections for energizing said network from one of said sources and for directly applying the other of said sources to the network as a comparative attenuation standard, and a timing device including an integrating instrument for measuring electrical energy and an amplifier for connecting the instrument to the output of the network, said amplifier being biased to conduct only during the respective time intervals required for attenuation between the limits of a potential equal in magnitude and opposite in polarity to the potential of said comparative standard and a potential with a magnitude determined by the magnitude of the potential of the energizing source whereby the instrument indication is proportional to the current pulses applied thereto, thereby to express a logarithmic correlation of the amplitudes of the input and output signals.

2. An electrical system with an output signal varying logarithmically with respect to the input signal comprising an attenuation network

having a logarithmic voltage time characteristic, a source of constant peak potential, a source of potential with a magnitude proportional to said input signal, connections for energizing said network from the source of constant peak potential and for applying the input signal source thereto as a comparative attenuation standard, and a timing device including an integrating instrument for measuring electrical energy and an amplifier for connecting the instrument to the output of the network, said amplifier being biased to conduct only during the respective time intervals required for attenuation between a potential equal in magnitude and opposite in polarity to the potential of said comparative standard and a potential with a magnitude determined by the magnitude of the peak potential and the rate of attenuation of said network whereby the instrument indication is proportional to the current pulses applied thereto, thereby to express a logarithmic correlation of the amplitudes of the input and output signals.

3. An electrical system with an output signal varying logarithmically with respect to an input signal comprising an attenuation network having a logarithmic voltage time characteristic, a constant peak potential source used as a comparative attenuation standard, a potential source proportional in magnitude to said input signal, connections for energizing said network from the source proportional to said input signal and for directly applying the constant peak potential source thereto, and a timing device including an integrating instrument for measuring electrical energy and an amplifier for connecting the instrument to the output of the network, said amplifier being biased to conduct only during the respective time intervals from the energization of said network by the source proportional to the input signal until the attenuation reaches a potential equal in magnitude and opposite in polarity to the potential of the comparative standard whereby the instrument indication is proportional to the current pulses applied thereto, thereby to express a logarithmic correlation of the input and output signals.

4. An electrical system with an output signal varying logarithmically with respect to an input signal comprising an attenuation network with a reactive impedance and a resistor connected in series therewith, a source of potential with a magnitude proportional to said input signal, a source of constant peak potential, connections including said resistor for energizing said impedance from one of said sources and for applying to the network the other of said sources as a comparative attenuation standard, and a timing device including an integrating instrument for measuring electrical energy and an amplifier for connecting the instrument to the output of the network, said amplifier being biased to conduct only during the respective time intervals required for attenuation between the limits of a potential equal in magnitude and opposite in polarity to the potential of said comparative standard and a potential with a magnitude determined by the magnitude of the potential of the energizing source, whereby the instrument indication is proportional to the current pulses applied thereto, thereby to express a logarithmic correlation of the amplitudes of the input and output signals.

5. An electrical system with an output signal varying logarithmically with respect to the input signal comprising an attenuation network with a reactive impedance and a resistor connected in

series therewith, a source of constant peak potential, a source of potential proportional in magnitude to said input signal, connections including said resistor for energizing said impedance from the source of constant peak potential and applying the potential source proportional to the input signal to the network as a comparative attenuation standard, and a timing device including an integrating instrument for measuring electrical energy and an amplifier for connecting the instrument to the output of the network, said amplifier being biased to conduct only during the respective time intervals required for attenuation between a potential equal in magnitude and opposite in polarity to the potential of the comparative standard and a potential with a magnitude determined by the magnitude of the peak potential and the rate of attenuation of said network whereby the instrument indication is proportional to the current pulses applied thereto, thereby to express a logarithmic correlation of the amplitudes of the input and output signals.

6. An electrical system with an output signal varying logarithmically with respect to an input signal comprising an attenuation network with a reactive impedance and a resistor connected in series, a source of potential proportional in magnitude to said input signal, a constant peak potential source used as a comparative attenuation standard, connections including said resistor for energizing said impedance from said source proportional to said input signal and for applying constant peak potential source to the network, and a timing device including an integrating instrument for measuring electrical energy and an amplifier for connecting the instrument to the output of the network, said amplifier being biased to conduct only during the respective time intervals from the energization of said network by the source proportional to said input signal until the attenuation reaches a potential equal in magnitude and opposite in polarity to the potential of the comparative standard whereby the instrument indication is proportional to the current pulses applied thereto, thereby to express a logarithmic correlation of the amplitudes of the input and output signals.

7. An electrical system with an output signal varying logarithmically with respect to an input signal comprising an attenuation network having a logarithmic voltage time characteristic, a square wave generator supplying a constant peak potential, a source of potential with a magnitude proportional to said input signal used as a comparative attenuation standard, connections for energizing said network from said square wave generator and for applying to the network the source proportional to the input signal, and a timing device including an integrating instrument for measuring electrical energy and an amplifier for connecting the instrument to the output of the network, said amplifier being biased to conduct only during the respective time intervals starting from the time the potential of the attenuation network is equal in magnitude and opposite in polarity to the potential of said comparative standard and terminating at the start of the next half-wave cycle whereby the instrument indication is proportional to the current pulses applied thereto, thereby to express a logarithmic correlation of the amplitudes of the input and output signals.

8. An electrical system with an output signal varying logarithmically with respect to an input signal comprising an attenuation network having

a logarithmic voltage time characteristic, an input signal source, a generator supplying square wave potential with an amplitude proportional to the magnitude of said input signal source, a direct potential source for use as a comparative attenuation standard, connections for energizing said network from said generator and for applying the direct potential thereto, and a timing device including an integrating instrument for measuring electrical energy and an amplifier for connecting the instrument to the output of the network, said amplifier being biased to conduct only during the respective time intervals from the energization of said network by said generator until the attenuation reaches a potential equal in magnitude and opposite in polarity to the potential of the comparative standard whereby the instrument indication is proportional to the current pulses applied thereto, thereby to express a logarithmic correlation of the amplitudes of the input and output signals.

9. An electrical system with an output signal varying logarithmically with respect to an input signal comprising an attenuation network having a logarithmic voltage time characteristic, a source of potential with a magnitude proportional to said input signal, a source of constant peak potential, connections for energizing said network from one of said sources and for applying thereto the other of said sources as a comparative attenuation standard, and a timing device including a vacuum tube amplifier having a grid and cathode connected to the output terminals of said network and an anode, a current limiter and a meter connected in series with said anode, said vacuum tube being biased so that current flows through the meter only during the time intervals required for attenuation between the limits of a potential equal in magnitude and opposite in polarity to the potential of said comparative standard and a potential with a magnitude determined by the magnitude of the potential of the energizing source whereby the meter indication is proportional to the duration of the current pulses applied thereto, thereby to express a logarithmic correlation of the amplitudes of the input and output signals.

10. An electrical system with an output signal varying logarithmically with respect to the input signal comprising an attenuation network having a logarithmic voltage time characteristic, a source of square wave potential, an input signal source used as a comparative attenuation standard, connections for energizing said network from the source of square wave potential and for applying the input signal source thereto, and a timing device including a vacuum tube amplifier having a grid and a cathode connected to the output terminals of said network and an anode, a current limiter and a meter connected in series with said anode, said vacuum tube being biased so that current flows through said meter only during the successive intervals starting from the time the potential of the attenuation network is equal in magnitude and opposite in polarity to the potential of said comparative standard and terminating at the start of the next half-wave cycle, whereby the meter indication is proportional to the duration of the current pulses applied thereto, thereby to express a logarithmic correlation of the amplitude of the input and output signals.

11. An electrical system with an output signal varying logarithmically with respect to an input signal comprising an attenuation network having a logarithmic voltage time characteristic, an in-

put signal source, a generator of square waves having an amplitude proportional to said input signal amplitude, a direct potential source used as a comparative attenuation standard, connections for energizing said network from said generator and for applying the direct potential source thereto, and a timing device including a vacuum tube amplifier having a grid and a cathode connected to the output terminals of said network and an anode, a current limiter and a meter connected in series with said anode, said vacuum tube being biased so that current flows through said meter only during the time intervals from the energization of said network by each of the successive waves from said generator until the wave potential attenuates to a potential equal in magnitude and opposite in polarity to the direct potential source whereby the meter indication is proportional to the duration of the current pulses applied thereto, thereby to express a logarithmic correlation of the amplitude of input and output signals.

12. An electrical system with an output signal varying logarithmically with respect to an input signal comprising an attenuation network having a logarithmic voltage time characteristic, a square wave generator with an output terminal connected to the input terminal of said network, two rectifying elements connected with said input signal source, one of said elements rectifying the positive portion of said signal, the other element rectifying the negative portion of said signal, a unidirectional element connecting the respective rectifying elements in the opposite sense with the output terminal of said generator so that the amplitude of the square wave potential impressed upon the network is proportional to said input signal, a constant direct potential connected to said network as a comparative attenuation standard, and a timing device including an integrating instrument for measuring electrical energy and an amplifier for connecting the instrument to the output of the network, said amplifier being biased to conduct only during each of the successive time intervals from the energization of said network by said generator until the attenuation reaches a potential equal in magnitude and opposite in polarity to the potential of the comparative standard whereby the instrument indication is proportional to the current pulses applied thereto, thereby to express a logarithmic correlation of the amplitudes of the input and output signals.

13. An electrical system with an output signal varying logarithmically with respect to an input signal comprising an attenuation network having a logarithmic voltage time characteristic, a square wave generator with an output terminal connected to the input terminal of said network, two rectifying elements connected with the input signal source, one of said elements rectifying the positive portion of said signal, the other element rectifying the negative portion of said signal, two unidirectional elements each connected in the opposite sense with the output terminal of said generator, a ripple filter coupling each of the unidirectional elements each connected in the opposite element so that the amplitude of the square wave potential impressed upon the network is proportional to said input signal, a constant direct potential connected to said network as a comparative attenuation standard, and a timing device including an integrating instrument for measuring electrical energy and an amplifier for connecting the instrument to the output of the network, said amplifier being biased to

conduct only during each of the successive time intervals from the energization of said network by said generator until the attenuation reaches a potential equal in magnitude and opposite in polarity to the potential of the comparative standard whereby the instrument indication is proportional to the current pulses applied thereto, thereby to express a logarithmic correlation of the amplitudes of the input and output signals.

14. An electrical system with an output signal varying logarithmically with respect to an input signal comprising an attenuation network having a logarithmic voltage time characteristic, a square wave generator with an output terminal connected to the input terminal of said network, a rectifying diode for the positive portion of said input signal having an anode linked with said signal source and a cathode, a limiter diode having a cathode coupled to the rectifying diode-cathode and an anode connected with the output terminal of said generator, a second rectifying diode for the negative portion of said input signal having a cathode linked with said signal source and an anode, a second limiter diode having an anode coupled to the second rectifying diode anode and a cathode connected with the output terminal of said generator, a direct power source connected to continuously circulate the small current through said diodes to increase the sensitivity and linearity thereof at low input signal levels, so that the amplitude of the square wave potential impressed upon said network is proportional to said input signal, a resistor connecting said source to said network to supply a positive potential as a comparative attenuation standard and a timing device including an integrating instrument for measuring electrical energy and an amplifier for connecting the instrument to the output of the network, said amplifier being biased to conduct only during each of the successive time intervals from the energization of said network by said generator until the attenuation reaches a potential equal in magnitude and opposite in polarity to the potential of the comparative standard whereby the instrument indication is proportional to the current pulses applied thereto, thereby to express a logarithmic correlation of the amplitudes of the input and output signals.

15. An electrical system with an output signal varying logarithmically with respect to an input signal comprising an attenuation network having a logarithmic voltage time characteristic, an input signal source, a source of square wave potential, connections for energizing said network from one of said sources and for applying thereto the other of said sources as a comparative attenuation standard, and a timing device including a vacuum tube amplifier having a grid and cathode connected to the output terminals of said network and an anode, a current limiter and a meter connected in series with said anode said vacuum tube being biased so that the current flows in the anode circuit only during the time interval required for attenuation between the limits of a potential equal in magnitude and opposite in polarity to the potential of said comparative standard and a potential with a magnitude determined by the amplitude of the square wave source potential, and a direct power source connected with said meter whereby a current is directed through the meter in a reverse direction when no current flows in the anode circuit whereby the meter indication is proportional to the duration of current pulses applied thereto, thereby to express a loga-

rithmic correlation of the amplitudes of the input and output signals.

16. An electrical system with an output signal varying logarithmically with respect to an input signal comprising an attenuation network having a capacitor and a resistor connected in series therewith, an input signal source linked with the input terminals of said network, a constant direct negative potential source used as a comparative attenuation standard, a vacuum tube amplifier having a grid and cathode coupled by said attenuation standard with the output terminals of said network and an anode, and an integrating instrument for measuring electrical energy connected in the circuit of said anode, said grid being biased so that the vacuum tube conducts only during the time interval from the energization of said network by said signal source until the attenuation reaches a potential equal in magnitude and opposite in polarity to that of said comparative standard whereby the instrument indication is proportional to the current pulses applied thereto, thereby to express a logarithmic correlation of the amplitude of the input and output signals.

17. An electrical system with an output signal varying logarithmically with respect to an input signal comprising an input signal source, an attenuation network including a reactive impedance and resistor series connected therewith, a square wave generator with an output terminal connected to the input terminal of said network, two rectifying elements connected with said input signal source one of said elements rectifying the positive portion of said signal, the other element rectifying the negative portion of said signal, two unidirectional elements each connected in the opposite sense with the output terminal of said generator, a ripple filter coupling each of the unidirectional elements with the respective rectifying elements so that the amplitude of the square wave impressed upon said network is proportional to said input signal, a constant positive potential source connected to said network as a comparative attenuation standard and a timing device including a vacuum tube amplifier having a grid and a cathode connected to the output terminals of said network and an anode, a unidirectional current limiter and a meter connected in series with said anode, said vacuum tube amplifier being biased so that current flows in the anode circuit only during each of the successive time intervals from the energization of said network by the generator until the potential reaches a potential equal in magnitude and opposite in polarity to the potential of the comparative attenuation standard whereby the meter indication is proportional to the duration of the current pulses supplied thereto, thereby to express a logarithmic correlation of the amplitude of the input and output signals.

18. An electrical system with an output signal varying logarithmically with respect to an input signal comprising an input signal source, an attenuation network including a reactive impedance and a resistor connected in series therewith, a full wave rectifier connected with said input signal source, a ripple filter coupling the rectifier with the input terminal of said network whereby a negative potential proportional to the amplitude of the input signal is impressed upon the network as a comparative attenuation standard, a square wave generator having an output terminal connected to the input terminal of said network, and a timing device including a vacuum tube having a grid and a cathode connected

to the output terminals of said network and an anode, a unidirectional current limiter and a meter connected in series with said anode, said vacuum tube being biased so that the current flows through said meter only during the successive intervals starting from the time the potential of the attenuation network is equal in magnitude and opposite in polarity to the potential of the comparative standard and terminating at the start of the next half square wave cycle whereby the meter indication is proportional to the duration of the current pulses applied thereto, thereby to express a logarithmic correlation of the amplitude of the input and the output signals.

19. An electrical system with an output signal varying logarithmically with respect to an input signal comprising an input signal source, an attenuation network including a capacitor and a resistor series connected therewith, a square wave generator with an output terminal connected to the input terminal of said network, a rectifying diode for the positive portion of said input signal having an anode linked with said signal source and a cathode, a ripple filter, a limiter diode having a cathode coupled to the rectifying diode cathode by said filter and an anode connected with the output terminal of said generator, a second rectifying diode for the negative portion of said input signal having a cathode linked with said signal source and an anode, a second ripple filter, a second limiter diode having an anode coupled to the second rectifying diode anode by said second filter and a cathode connected with the output terminal of said generator, a direct power source, a connection to continuously circulate a small current through said diodes to increase the sensitivity and linearity thereof at low input signal levels so that the amplitude of the square wave impressed upon the network is proportional to said input signal, a resistor connecting said direct power source to said network to supply a comparative attenuation standard potential, a timing device including a two stage amplifier having two interconnected vacuum tubes each having a cathode, a grid and an anode, the first stage grid and cathode being connected to the output terminals of said attenuation network, a series resistor connecting the first stage anode to the output terminal of said generator, said anode also being directly linked to the second stage grid, a resistor connecting the second stage anode to the power source, a unidirectional current limiter and a meter connected in series between the second stage anode and the power source whereby during the time interval from the energization of the network by a negative wave from the square wave generator until the attenuation reaches a potential equal in magnitude and opposite in polarity to the comparative standard potential, the resultant negative potential on the grid prevents the first stage tube from conducting so that the positive potential on the second stage grid causing a current to flow through said meter, and connections between the power source and said meter directing a reverse current therethrough in the absence of current in the circuit of said second stage anode during the intervals when the first stage grid is at a positive potential, whereby the meter indication is proportional to the duration of the current pulses applied thereto, thereby to express a logarithmic correlation of the amplitudes of the input and output signals.

20. An electrical system with an output signal

varying logarithmically with respect to an input signal comprising an input signal source, an attenuation network including a capacitor and a resistor series connected therewith, a full wave rectifier connected with said input signal source, a ripple filter coupling the rectifier with the input terminals of said attenuation network whereby a negative potential proportional to the amplitude of the input signal is impressed upon the network as a comparative attenuation standard, a square wave generator having an output terminal connected to the input terminal of said network, a direct power source, a bleeder resistor connected to said power source, a diode having a cathode connected to the more positive terminal of said bleeder resistor and an anode connected to the output terminal of said generator thereby to limit the positive peak amplitude of the square wave from said generator, a second diode having an anode connected to the more negative terminal of said bleeder resistor and a cathode connected to the output terminal of said generator thereby to limit the negative peak amplitude of the square wave from said generator, and a timing device including two vacuum tubes interconnected as a two-stage amplifier and each having a cathode, a grid and an anode, the first stage grid and cathode being connected to the output terminals of said attenuation network, a series resistor connecting the first stage anode to the output terminal of said generator, said anode also being directly linked to the second stage grid, a resistor connecting the second stage anode to the power source, a current limiter and a meter connected in series between the second stage anode and the power source whereby during the interval beginning at the time the potential of the attenuation network is equal in magnitude and opposite in polarity to the potential of the comparative standard and terminating at the start of the next half-way cycle by the reversal of polarity of the potential upon the first stage anode so that the meter indication is proportional to the duration of the current pulses applied thereto, thereby to express a logarithmic correlation of the amplitude of the input and output signals.

21. An electrical network for completely cutting off the flow of current in the output circuit in response to a predeterminate change in the potential of an input signal comprising a direct power source, an input signal source, a two-stage amplifier including two interconnected vacuum tubes each having a cathode, a grid and an anode, the first stage grid and cathode being connected to the output terminals of said input signal source, a series resistor connecting the first stage anode to the direct power source, said anode also being directly linked to the second stage grid, a resistor connecting the second stage anode to the power source, and a unidirectional element connected in series with the output terminals between the second stage anode and the power source in parallel with the resistor connecting the second stage anode to the power source, whereby the application to the first stage grid of a signal having a potential characteristic to cause a current flow through the resistor in series with the first stage anode results in a voltage drop which impresses upon the second stage grid negative potential sufficient to cut off the second stage tube so that a positive potential is impressed upon the unidirectional element in the sense to prevent said element from conducting.

22. An electrical network for completely cutting off the flow of current in the output circuit in response to a predeterminate change in the potential of an input signal comprising a direct power source having a voltage apportioning impedance connected thereto, an input signal source, a two-stage amplifier including two interconnected vacuum tubes each having a cathode, a grid and an anode, the first stage grid and cathode being connected to the output terminals of said input signal source, a series resistor connecting the first stage anode to the direct power source, said anode also being directly linked to the second stage grid, a resistor connecting the second stage anode to the power source, and a unidirectional element connected in series with the output terminals of said network between the second stage anode and a portion of said impedance at a lower voltage than the power source, whereby the application to the first stage grid of a signal having a potential characteristic to cause a current flow through the resistor in series with the first stage anode results in a voltage drop which impresses upon the second stage grid a negative potential sufficient to cut off the second stage tube so that a positive potential is impressed upon the unidirectional element in the sense to prevent said element from conducting.

23. An electrical system with an output signal varying logarithmically with respect to an input signal comprising an input signal source, an attenuation network including a capacitor and a resistor series connected therewith, a square wave generator with an output terminal connected to the input terminal of said network, a rectifying diode for the positive portion of said input signal having an anode linked with said signal source and a cathode, a ripple filter, a limiter diode having a cathode coupled to the rectifying diode cathode by said filter and an anode connected with the output terminal of said generator, a second rectifying diode for the negative portion of said input signal having a cathode linked with said signal source and an anode, a second ripple filter, a second limiter diode having an anode coupled to the second rectifying diode anode by said second filter and a cathode connected with the output terminal of said generator, a direct power source having a voltage apportioning impedance connected thereto, a connection to said impedance for continuously circulating the small current through said diodes to increase the sensitivity and linearity thereof at low input signal levels so that the amplitude of the square wave impressed upon the network is proportional to said input signal, a resistor connecting said voltage apportioning impedance to said network to supply a comparative attenuation standard potential, a timing device including a two stage amplifier having two interconnected vacuum tubes each having a cathode, a grid and an anode, the first stage grid and cathode being connected to the output terminals of said attenuation network, a series resistor connecting the first stage anode to the direct power source, said anode also being directly linked to the second stage grid, a resistor connecting the second stage anode to the power source, a unidirectional current limiter and a meter connected in series between the second stage anode and a portion of said impedance at a lower potential than the power source, said second stage cathode being connected to a portion of said impedance at a lower potential than the meter connection,

5 whereby during the time interval from the energization of the network by a negative wave from the square wave generator until the attenuation reaches a potential equal in magnitude and opposite in polarity to the comparative standard potential, the resultant negative potential on the grid prevents the first stage tube from conducting so that the positive potential on the second stage grid causing a current to flow through said meter, and connections between the power source and said meter directing a reverse current therethrough in the absence of current in the circuit of said second stage anode during the intervals when the first stage grid is at a positive potential, 10 15 whereby the meter indication is proportional to the duration of the current pulses applied thereto, thereby to express a logarithmic correlation of the amplitudes of the input and output signals.

24. An electrical system with an output signal varying logarithmically with respect to an input signal comprising an input signal source, an attenuation network, including a capacitor and a resistor series connected therewith, a full wave rectifier connected with said input signal source, 20 25 a ripple filter coupling the rectifier with one of the input terminals of said attenuation network whereby a negative potential proportional to the amplitude of the input signal is impressed upon the network as a comparative attenuation standard, a square wave generator having an output terminal connected to the second input terminal of said network, a direct power source having a voltage apportioning impedance connected thereto, a bleeder resistor connected to said power source, a diode having a cathode connected to the more positive terminal of said bleeder resistor and an anode connected to the output terminal of said generator thereby to limit the positive peak amplitude of the square wave from said 30 35 generator, a second diode having an anode connected to the more negative terminal of said bleeder resistor and a cathode connected to the output terminal of said generator thereby to limit the negative peak amplitude of the square wave from said generator, and a timing device including two vacuum tubes interconnected as a two stage amplifier and each having a cathode, a grid and an anode, the first stage grid and cathode being connected to the output terminals of said 40 45 50 55 60 65 70 attenuation network, a series resistor connecting the first stage anode to the output terminal of said generator, said anode also being directly linked to the second stage grid, a resistor connecting the second stage anode to the power source, a current limiter and a meter connected in series between the second stage anode and a portion of the impedance at a lower potential than the power source said second stage cathode being connected to a portion of said impedance at a lower potential than the meter connection, whereby during the interval beginning at the time the potential of the attenuation network is equal in magnitude and opposite in polarity to the potential of the comparative standard and terminating at the start of the next half-way cycle by the reversal of polarity of the potential upon the first stage anode so that the meter indication is proportional to the duration of the current pulses applied thereto, thereby to express a logarithmic correlation of the amplitude of the input and output signals.
